ANDREW J. CULBERTSON, OF SAN ANDREAS, CALIFORNIA, ASSIGNOR
TO JOHN W. STROUGH, OF SAME PLACE, AND EDWARD L. BURNS.
OF CORONTO-GARGADENNES, CALIFORNIA.

PNEUMATIC PROPELLING MEANS FOR VESSELS.

SPECIFICATION forming part of Letters Patent No. 608,757, dated August 9, 1898.

Application filed October 9, 1897. Serial No. 654,671. (No model.)

To all whom it may concern:

Be it known that I, ANDREW J. CULBERTSON, of San Andreas, in the county of Calaveras and State of California, have invented 5 a new and useful Improvement in the Construction of Vessels, of which the following is a full, clear, and exact description.

The object of the invention is to provide a construction of a hull whereby the water will 10 have the least possible frictional engagement with the hull and whereby, further, it will be rendered possible to interpose currents of air at various points between the hull and the water in which the hull rests for the dual 15 purpose of forcing the vessel ahead and assisting the driving mechanism employed and also preventing the water from retarding the progress of the vessel.

Another object of the invention is to provide 20 a means whereby the currents of air which serve as a cushion may be utilized in steering the vessel or quickly turning its head to port or starboard.

The invention consists in the novel construction and combination of the several parts, as will be hereinafter fully set forth, 25 and pointed out in the claims.

Reference is to be had to the accompanying drawings, forming a part of this specification, 30 in which similar characters of reference indicate corresponding parts in all the figures.

Figure 1 is a longitudinal vertical section through a vessel having the improvement applied. Fig. 2 is a bottom plan view of the 35 hull. Fig. 3 is a cross-section through the hull, taken at a point near the bow. Fig. 4 is a longitudinal section through a portion of the bow, showing the air-pumps in side elevation and the manner in which the air is directed therefrom to channels or chambers at the bottom of the hull; and Fig. 5 is a sectional view of a row-boat to which the improvement is applied.

The improvement is applicable to boats of 45 any description.

A represents the interior of a boat, adapted for use in shallow water, and at the bottom of the hull longitudinal cleats B are formed at each side of the keel B'. These cleats ex-

tend practically from the bow to the stern, 50 and between the cleats channels or chambers 10 are formed. The lower deck 11 is built in the usual manner over the bottom portion 12 of the hull, and on this lower deck 11, at the bow of the vessel, a number of air-pumps 55 or air-compressors C, of any approved construction, are located, an air-pump being provided for each of the channels or chambers 10. The air-pumps are fitted with pipes 13, which extend in the direction of the channels 60 or chambers 10, as best shown in Fig. 3, and auxiliary elbow-pipes 13^a are connected with the outlet-pipes 13 of the air-pumps, preferably by a slip-joint of any construction that will permit the elbow-pipes to move up and 65 down and also turn upon the outlet-pipes of the pumps. The elbow-pipes 13^a may be termed "air-exit" pipes, and, normally, their outlets are contained within the channels or chambers 10, facing the stern, as shown in Fig. 1. 70 The air-exit pipes may be used at any time for assisting the rudder in turning the vessel. When so used, the air-exit pipes are dropped until their outlets are below the hull, and the pipes are then turned in a direction to force the bow to one side or the 75 other by the impact of the column of air leaving the exit-pipes and striking the water, as shown in Fig. 4. The channels or chambers 10 are open at the stern, so that the air 80 introduced into them may find a free exit. At the stern end of each cleat B and at the stern end of the keel B' an auxiliary cleat 14 is illustrated, the auxiliary cleats being substantially continuations of the cleats of the 85 keel or the main cleats at the bottom of the vessel. Each auxiliary cleat is also shown as provided with an upwardly-extending post 15, each post having a crank-arm 16, the various crank-arms being connected by one or 90 more links 17 or a suitable connecting-rod, so that all the auxiliary cleats may be moved simultaneously in the same direction when desired to assist in steering; but the auxiliary cleats may be omitted, together with the 95 parts connected therewith, if desired.

It will be observed that the cleats are in parallel lines and that when air is not intro-

duced into the chambers between the cleats the said cleats will serve as auxiliary keels or fins, and they will not in any manner interfere with the progress of the boat when air 5 is not supplied to the chambers or channels 10. The cleats B may be quite shallow. In fact, the width of the cleats or their dimensions will be governed largely by the character of the stream or body of water in which 10 the boat is to do service,

When the pumps C are in operation, air is forced continuously into the channels or chambers 10 from the bow, and the air will pass to the stern in wave-lines, as indicated 15 in Fig. 1, and will present a cushion intervening the hull and the water. Consequently the boat will move to a greater extent on sheets or cushions of air than on the water, although the water will engage with the auxiliary keels or the cleats.

As heretofore stated, the connection between the pipes 13, leading from the air-pumps, and the pipes 13^a, that direct the air to the channels or chambers, may be accomplished in any well-known way. In the drawings each air-exit pipe 13^a is shown as provided with an upwardly-extending arm 18, terminating in a handle 19, and by means of the latter or a lever connected therewith the 25 air-exit pipe 13^a may be vertically adjusted 30 or turned to the right or to the left.

In Fig. 5 I have illustrated the application of the improvement to a row-boat D, the boat being provided with one or more, preferably 35 two, air-compressors C'. The piston-rods 20 from the air-compressors may be passed through suitable guides secured to the sides of the boat, and thence upward to an engagement 40 with the handle portion of the oar or scull 21, or directly, as illustrated, the said attachment being made inside of the oar-lock 22.

The invention is especially applicable to row-boats, racing-shells, and boats of similar construction, in which, as shown in Fig. 5, 45 the oars or sculls may be utilized as pump levers or handles. This attachment to row-boats will render boating more pleasurable and will serve to increase the speed of boats.

and reduce the labor of rowing. When an attachment is made between the pistons of the 50 air-compressors and the oars or sculls, the oar-lock constitutes the hinge or pivot point, and the length of the rowing stroke will regulate the stroke of the piston-rod.

Having thus described my invention, I 55 claim as new and desire to secure by Letters Patent—

1. In the construction of vessels, a hull provided with a series of cleats arranged longitudinally and forming a series of channels 60 open at the bottom and at the stern, means, substantially as described, for forcing a buoyant material through said channels, and also for directing the buoyant material against the water below the cleats to assist in steering, substantially as described.

2. In the construction of vessels, a hull provided with a series of cleats arranged longitudinally, forming a series of channels open at the bottom and at the stern, air-compressors located above the channels, and pipes leading from the air-compressors into the said channels at the bow portion of the boat, the said pipes being outlet-pipes for the compressors and constructed in sections, the lower sections of the outlet-pipes being capable of vertical and lateral movement, as and for the purpose set forth.

3. In the construction of vessels, a hull provided with a series of longitudinal cleats in parallel arrangement, forming a series of parallel chambers or channels open at the bottom and at the rear, air-pumps connected with said chambers or channels at their forward ends, and a series of auxiliary rudders forming a continuation of each of said ribs, the rudders being at the rear, and means for connecting the said auxiliary rudders, whereby they may be simultaneously moved in direction of the port or the starboard side of the vessel, as and for the purpose specified.

ANDREW J. CULBERTSON.
